UNITED STATES PATENT OFFICE.

MEYER DAVIS, OF CHICAGO, ILLINOIS.

DESIGN FOR A PHONOGRAPH-CABINET.

55,415.

Specification for Design.

Patented June 8, 1920.

Application filed October 24, 1919. Serial No. 333,134. Term of patent 14 years.

To all whom it may concern:

Be it known that I, MEYER DAVIS, a citizen of the United States, residing at Chicago, in the county of Cook and State of Illinois, have invented a new, original, and ornamental Design for Phonograph-Cabinets, of which the following is a specification, reference being had to the accompanying drawing, forming part thereof.

As shown in this drawing, Figure 1 is a perspective view of a phonograph cabinet showing my new design; and Fig. 2 is a plan view of the same.

I claim:

The ornamental design for a phonograph cabinet as shown.

MEYER DAVIS.
